Primary Examiner — Mark A Goodwin(74) *Attorney, Agent, or Firm* — Guy Levi; The IP Law Firm of Guy Levi, LLC(57) **CLAIM**

I claim, the ornamental design for a hemispheric peg support, as shown and described herein.

DESCRIPTION

FIG. 1, is a bottom perspective view of the hemispheric peg support, showing my new design;

FIG. 2, is another bottom perspective view thereof;

FIG. 3, is a top plan view thereof;

FIG. 4, is a bottom plan view thereof;

FIG. 5, is an elevation view thereof, the hemispheric peg support being symmetric; and,

FIG. 6, is a cross section of FIG. 5.
